CLAIM

The ornamental design for a jewelry link, as shown and described.

DESCRIPTION

FIG. 1 is a perspective view of a jewelry link showing my new design;

FIG. 2 is a top plan view;

FIG. 3 is a side elevational view;

FIG. 4 is a front elevational view;

FIG. 5 is a rear elevational view; and,

FIG. 6 is a bottom plan view.

The broken line showing of adjacent jewelry links, in FIG. 2 is for illustrative purposes only and forms no part of the claimed design.
